UNITED STATES PATENT OFFICE.

CARL AMMENTORP, OF COPENHAGEN, DENMARK.

ELECTRIC CANDLE.

1,306,990.

Specification of Letters Patent. Patented June 17, 1919.

Application filed March 31, 1917. Serial No. 158,883.

To all whom it may concern:

Be it known that I, CARL AMMENTORP, subject of the King of Denmark, residing at No. 23 St. Pederstraede, Copenhagen, Denmark, have invented certain new and useful Improvements in Electric Candles; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 The electric incandescent lamps with candle-like, white glass or opalescent bodies directly connected with the bulb (genuine English electric candles) are comparatively expensive, and when the filament breaks 20 they have to be entirely discarded. Therefore attempts have been made to combine common Mignon-bulbs with detachable, candle-like, white glass cylinders by inserting, between the bulb and the foot of the 25 candle-like cylinders, a special adjustable frame hidden from view by the white glass. These imitations of English electric candles have, however, essential faults. They have a heterogeneous, or non-uniform appear- 30 ance; they rattle, and are difficult to install in the glass cylinders, so that the bulbs stand straight and fit properly against the edges of the cylinders.

These disadvantages are avoided by means 35 of the present invention, which is chiefly characterized in that the candle-like cylinder itself serves as a mounting - element, which is connected with the bottom-piece, and which, by suitable friction, holds fast 40 a lamp-holder not rigidly connected with the bottom-piece.

One form of construction is shown, by way of example, in the drawing.

The candle-like cylinder 1 has at its bot- 45 tom a suitable fitting 2 which, by means of screw-socket, bayonet-lock, or the like, can hold it in the chandelier lamp-socket, and

at the same time establish current-connection, with contacts 3. The bulb-plug 4, or its insulator 5, is connected with the contacts by means of flexible slack wires 6, and is so constructed that it fits into the cylinder in frictional contact therewith so that it can easily be pushed in or pulled out by grasping the bulb 7, while the latter, when it is 50 pushed down into the position shown in the drawing, rests on the upper edge of the cylinder. The necessary friction between the cylinder and the bulb-holder, and the centering of the latter may be accomplished, as 55 shown in the drawing, by means of a ring 8 of rubber or similar material, which is disposed between the insulator 5 of the bulb holder and an insulating-nut 9 screwed on to the bulb-plug 4, so that it can be ex- 60 panded more or less by turning the nut.

The electric candles here referred to are easy to mount, since the wires 6 are so long that they can reach above the top edge of the cylinder when they are to be clamped 70 into the bulb-holder. The latter (with bulb screwed in) is then pushed into place, when the wires 6 collapse or, by turning the bulb are coiled together, as shown, in the lower part of the cylinder. There is no other height- 75 adjustment to be made, except the extremely simple operation of pushing the bulb down to the upper edge of the cylinder. It will then rest just as solidly on the cylinder as if it were a part of it, and there will be no 80 rattling.

I claim:—

An electric candle comprising an opalescent tube having a socket member secured to its base, a bulb holder within the tube, slack 85 wires connecting the holder and base, said holder including a base portion and a bulb plug, a nut on said plug and an expansible friction member on said plug and included between said nut and base portion. 90

In testimony that I claim the foregoing as my invention, I have signed my name.

CARL AMMENTORP.
